(57) **CLAIM**

The ornamental design for a modular target stand, as shown and described.

DESCRIPTION

FIG. 1 is a perspective front view of a modular target stand showing my new design;

FIG. 2 is a right side view thereof;

FIG. 3 is a perspective front view of a modular target stand without its arms;

FIG. 4 is a perspective view of the arms;

FIG. 5 is another perspective view of the arms;

FIG. 6 is a top view of the arms;

FIG. 7 is a bottom view of the arms;

FIG. 8 is a side view of the arms; and,

FIG. 9 is a perspective view of the modular target stand with targets inserted.

The broken lines shown in the figures are for illustrative purposes only and are not part of the claimed design.
